ELECTRIC VAPOR-LAMP AND THE LIKE.

1,164,603.

Specification of Letters Patent. Patented Dec. 14, 1915.

Application filed September 25, 1914. Serial No. 863,565.

To all whom it may concern:

Be it known that I, JULIUS JONAS, a subject of the Emperor of Germany, and residing at Bruggerstrasse 22, Baden, Switzerland, have invented certain new and useful Improvements in and Relating to Electric Vapor-Lamps and the like, of which the following is a specification.

This invention relates to electric vapor lamps and the like.

It is well known that for certain purposes the electric arcs in such apparatus have to be electromagnetically controlled, see for instance my application Serial No. 854457. 15 This can readily be effected in the case of lamps or the like in glass vessels but not so when they are contained in metal vessels, because eddy currents will be introduced in the metal wall and in other ways the magnetic flux will be prevented from influencing the arc.

The present invention has for its object to provide an apparatus for magnetically influencing an electric arc in a metal vacuum vessel wherein the aforesaid injurious effects will not take place.

The invention consists in so constructing and disposing the magnet that penetration of the metal wall by lines of force is almost wholly avoided, for example, by arranging the blowing magnet entirely inside the metal vessel.

In the accompanying diagrammatic drawings: Figure 1 shows a sectional elevation of one form of the present invention; Fig. 2 is a section on the line 2—2 of Fig. 1 looking in the direction of the arrows; Fig. 3 is a sectional plan of a modification (on the line 3—3 of Fig. 4), and Fig. 4 is a sectional elevation corresponding thereto. Fig. 5 is a section on the line 5—5 of Fig. 4. Fig. 6 is a sectional elevation of a further modification. Fig. 7 is a sectional plan of Fig. 6 on the line 7—7, and Fig. 8 is a section on the line 8—8 of Fig. 6.

In Figs. 1 and 2 the magnet *m* is arranged wholly inside the vessel *g*. Thus the flux of the magnet does not pass through the metal wall so that the aforesaid injurious effects do not take place. In this form the electric arc is led through a glass, porcelain or like electrically non-conducting tube *x* for the purpose of keeping the electric arc and the mercury vapors away from the winding of the magnet, which winding is preferably

formed of enameled wire. Then the electric arc is led through a glass tube or the like, this by concentration will be favorable to the action of the magnet. The glass tube will not be exposed to a one-sided pressure, 60 because there is a vacuum both inside the tube and in the space surrounding said tube.

While any connections or arrangements may be used for producing the light arc indicated by *l*—it only being necessary for the present invention to assume that such arc is there—the arrangement referred to above is applied in an apparatus as shown in Fig. 3 of my copending application No. 854457. 65 In this case the arc is produced between mercury electrodes *q* in the glass cell *x* containing mercury vapor under diminished pressure. The electrodes are connected to a battery *z* and primary of a transformer *y*. The winding *w* is excited by the alternator *l'*. 70 The apparatus of Figs. 3 to 5 comprises a metal vessel *g* containing in its interior a sheet partition *s* and of a further vessel *d* which carries two mercury electrodes *q*, *q*, and the electromagnet *m* including the poles *p*¹ *p*², and the winding *w*. By the action of the magnet the electric arc is blown against the edge of the partition *s* and into the space *c*, *c*.

In Figs. 5 and 6 the yoke and the winding *w* of the magnet *m* are situated outside the metal vessel, and only the poles are brought into the interior of the vessel. In order however, to prevent the occurrence of eddy currents in the metal wall *g*, it is formed with 90 a slot *u* between the arms of the magnet. The aperture is closed by means of a non-conducting material. The resulting field in the aperture of the metal wall thus formed is then *nil*. 95

A partition *s* as shown in Fig. 4 may be used in other forms, for example, that shown in Figs. 5 and 6.

Igniting electrodes or other usual accessories may be incorporated when desired. 100

Having now described my invention, what I claim as new and desire to secure by Letters Patent is:—

1. Vapor electric apparatus comprising in combination an evacuated metal container, 105 two electrodes within said container at least one of said electrodes being a mercury electrode, a source of direct current and a transformer with primary and secondary windings, an electrical connection from one elec- 110

trode to the source of direct current, from that source to one of the windings of the transformer and from that winding to the other electrode, an electromagnet with poles 5 situate within the metal container and disposed with its poles in such relation to the arc path between the electrodes as to form a blowing magnet with respect to the arc, a source of alternating current situate outside 10 the container and connected to the windings of the electromagnet together with means for restricting the path of the arc between the electrodes in the vicinity of the electromagnet to an area substantially equal to 15 that inclosed between the poles of said magnet.

2. Vapor electric apparatus comprising in combination an evacuated metal container, two electrodes within said container, at least 20 one of said electrodes being a mercury electrode, means for causing an arc to pass from one electrode to the other, an electromagnet situate wholly within said container and a source of alternating current for exciting 25 said electromagnet, the poles of the electromagnet being so disposed in relation to the arc path between the electrodes that the magnet acts as a blowing magnet toward said arc and means for restricting the passage 30 of the arc in the vicinity of the electromagnet to an area substantially equal to that inclosed between the poles of the magnet.

3. Vapor electric apparatus comprising 35 an evacuated metal container, electrodes of mercury within said container and means for causing the passage of an arc between the electrodes, an electromagnet disposed in

the container, the poles of the electromagnet being so disposed in relation to the arc path 40 between the electrodes that the magnet acts as a blowing magnet as regards said arc, a source of alternating current for exciting said magnet and a thin shield depending from the top of the container substantially 45 to the poles of the magnet to restrict the passage of the arc between the electrodes in the vicinity of the magnet to an area substantially equal to that contained between the poles of the magnet. 50

4. Vapor electric apparatus comprising in combination an evacuated metal container, two electrodes within said container, at least one of said electrodes being a mercury electrode, terminals outside the container 55 and electrical connections from said terminals to said electrodes, an electromagnet situate within the metal container and disposed with its poles in such relation to the arc path between the electrodes as to form a 60 blowing magnet with respect to the arc, means for restricting the path of the arc between the electrodes in the vicinity of the electromagnet to an area substantially equal to that inclosed between the poles of said 65 magnet, and terminals outside the container, together with electrical connections from said terminals to the windings of the electromagnet within the container.

In testimony whereof, I have affixed my 70 signature in presence of two witnesses.

JULIUS JONAS.
